UNITED STATES PATENT OFFICE

2,412,100

PROTRACTOR

Neil C. Smith, Minneapolis, Minn.

Application November 29, 1944, Serial No. 565,697

3 Claims. (Cl. 33—94)

1

My present invention relates to improvements in protractors of the type having a rotatable turret and a blade slidably mounted thereon.

The object of this invention is to provide an extremely simple and highly efficient protractor having common means for simultaneously locking the turret against rotation and the blade against sliding movement.

Other objects of the invention will be apparent from the following description, reference being had to the accompanying drawing.

To the above end, generally stated, the invention consists of the novel devices and combination of devices hereinafter described and defined in the claims.

In the accompanying drawing, which illustrates the invention, like characters indicate like parts throughout the several views.

Referring to the drawing:

Fig. 1 is a plan view of the improved protractor;

Fig. 2 is a bottom plan view of the turret and the blade removed from the body of the protractor;

Fig. 3 is a fragmentary plan view of the body with the turret and the blade removed therefrom;

Fig. 4 is a view partly in side elevation and partly in section taken on the line 4—4 of Fig. 1, on an enlarged scale;

Fig. 5 is a plan view of the washer removed from the protractor, as shown in Fig. 4; and

Fig. 6 is a bottom plan view of the washer as shown in Fig. 5.

The numeral 7 indicates the body of the protractor which, as shown, is in the form of a blade, the longitudinal edges of which are parallel. One end portion of the body 7 is enlarged to afford a head 8. At the center of the head 8 is an upstanding tubular pivot 9, the lower end portion of which is reduced in diameter and mounted in a hole in said head. An annular shoulder 10 is formed by reducing the lower end portion of the pivot 9 and which shoulder 10 rests directly on the head 8. The lower end of the pivot 9 is upset within the plane of the body 7 to rigidly secure the pivot 9 to the head 8 with its axis perpendicular to the plane of the body 7. This method of securing the pivot 9 to the head 8 leaves the bottom of the body 7 perfectly smooth so that said body will rest flat on a support.

A flat turret 11 is mounted on the pivot 9 for rotation about the axis thereof in a plane parallel to the plane of the body 7. Substantially 180 degrees of the turret 11 is on the arc

2

of a circle having its center at the axis of said turret 11. This section of the turret 11 is beveled to a relatively sharp edge at its under side, as indicated at 12.

5 A thin narrow blade 13 is mounted in a channel 14 in the under side of the turret 11 for endwise sliding movement. This channel 14 is in the opposite side of the turret 11 from the intermediate portion of the bevel 12. A spring member 15 in the channel 14, between one side thereof and the adjacent longitudinal edge of the blade 13, yieldingly holds said blade pressed against the other side of said channel whereby the blade 13 is frictionally held where endwise 10 adjusted in the channel 14. The spring member 15 is held in the channel 14 by a pin 16. The blade 13 rests flatwise directly on the head 8 and the central portion of the turret 11 also rests directly on said head. Said turret 11, at its outer 15 portion, has a working clearance with the body 1, see Fig. 4.

The longitudinal edge of the blade 13 that is in direct engagement with the side of the channel 14 has dove-tailed engagement with the 20 turret 11. The upper end portion of the pivot 9 extends outwardly of the turret 11 and is reduced in diameter and diametrically opposite sides of this reduced portion are flattened, as indicated at 17. A washer 18 is mounted on 25 the reduced outer end portion of the pivot 9 and the hole therein has the same contour as the respective portion of the pivot 9 and is thereby held from turning on the pivot 9. The under side of the washer 18 is dished at 19 so that only 30 its outer marginal portion bears on the turret 11. The reduced outer end portion of the pivot 9 and the hole therein has the same contour as the respective portion of the pivot 9 and is thereby held from turning on the pivot 9. The under side of the washer 18 is dished at 19 so that only 35 its outer marginal portion bears on the turret 11.

A screw 20 extends into the tubular pivot 9 and has threaded engagement therewith. This screw 20 has a large head 21, the periphery of which is beveled and knurled. On the under 40 side of the screw head 21 is a thin hub 22 that bears directly on the washer 18.

Obviously, by tightening the screw 20, the 45 turret 11 will be frictionally clamped onto the body 7 and thereby held against rotation and at the same time the blade 13 will be frictionally clamped onto the body 7 and thereby held against endwise sliding movement. It will be noted that the screw head 21 extends outwardly of the washer 18 so that the same can be easily gripped with the fingers. The size of the screw head 21 makes it very easy to manipulate. The 50 turret 11, the washer 18, the screw 20 and the screw head 21 all have their axis at the axis of the pivot which lends itself for accuracy and easy assembly. The washer 18, due to its dished

under side, bears only on its outer portion on the turret 11. This structure gives an even pressure on the turret in a complete circle that is concentric to the pivot 9, thereby holds the turret 11 in a plane that is parallel to the plane of the body 7 and prevents tilting thereof on the pivot 9 and thus prevents undue wear and strain on said pivot.

By reference to Fig. 4 it will be noted that there is a working clearance between the upper end of the pivot 9 and the hub 22. The dished under side of the washer 18 affords a good working clearance between the shouldered upper end of the pivot 9 and said washer and the surface of the turret 11 underlying said dished portion of the washer 18.

The body 7 and the blade 13 each has thereon a scale of inches as indicated at 23 and 24, respectively. A circle, outward of the curved portion of the turret 11 and having its center at the axis of the pivot 9 is divided into quarters, and each quarter graduated into 90 degrees, as indicated at 25. These degrees read from two diametrically opposite zero points. Two zero marks 26 and 27 are shown on the turret 11 spaced 90 degrees apart for co-operation with the degree graduations 25. By means of one of these zero points 25 and 26, the turret 11 may be adjusted to position the blade 13 at a required angle relative to the body 7 and the degree reading at the other zero point will give the component angle. A vernier scale 28 on the turret 11 has its zero point at the zero point 27 and reads in opposite directions therefrom. The close proximity of the beveled edge of the turret 11 with the degree markings 25 lends itself to easy and accurate reading of said degrees.

What I claim is:

1. In a device of the class described, a body

having an upstanding pivot, a turret turnably mounted on the pivot with freedom for axial movement and resting on the body, a blade mounted on the turret for endwise sliding movement and resting on the body, a washer mounted on the pivot with freedom for axial movement, held against relative turning movement and resting on the turret, a member having threaded engagement with the pivot and bearing on the washer and operable to simultaneously frictionally clamp the turret onto the body and thereby hold the turret from turning on the pivot and frictionally clamp the blade between the body and the turret and thereby hold the blade from sliding endwise relative to the turret and the body.

2. In a device of the class described, a body having an upstanding tubular pivot, a turret turnably mounted on the pivot with freedom for axial movement, resting on the body, and having a channel in its under side, a blade mounted in said channel for endwise sliding movement and resting on the body, a washer mounted on the pivot with freedom for axial movement, held against relative turning movement and resting on the body, a thumb-screw having threaded engagement with the tubular pivot with its head bearing on the washer and operable to simultaneously frictionally clamp the turret onto the body and thereby hold the turret from turning on the pivot and frictionally clamp the blade between the body and the turret and hold the blade from sliding endwise relative to the turret and the body.

3. The structure defined in claim 2 in which the washer is dished on its under side and thereby engages the turret only at its perimeter.

NEIL C. SMITH.
